UNITED STATES PATENT OFFICE.

FRANZ VINCENT, OF BRIDGEPORT, CONNECTICUT.

POWDER PUFF.

Application filed August 31, 1925. Serial No. 53,522.

This invention relates to a vanity box, and has for an object to provide an improved box of this type in which the powder is not carried loose in the box where it can be spilled or contaminated, and also in which the powder is not carried as a compact.

It is also an object of the invention to provide an improved powder puff which will act as a loose powder container, and which is so constructed that under ordinary handling the powder will be held in the container but is accessible in proper amounts as required.

With the foregoing and other objects in view, I have devised the construction illustrated in the accompanying drawing forming a part of this specification, similar reference characters being employed throughout the various figures to indicate corresponding elements. In this drawing,—

Fig. 1 is a top plan view of the box in open position.

Fig. 2 is a transverse vertical section through the same in closed position and on a somewhat enlarged scale.

Fig. 3 is a top plan view of the rubber powder container removed from the box.

Fig. 4 is an edge view thereof.

Fig. 5 is a view similar to Fig. 4 showing the filling opening at the side of the sack in open position.

Fig. 6 is a plan view of a puff constructed according to my invention.

Fig. 7 is a transverse section thereof substantially on line 7-7 of Fig. 6, and

Fig. 8 is a transverse section through a box with the improved form of puff shown in Figs. 6 and 7 therein.

My improved box comprises a body section 10 and a cover section 11, preferably hinged together by the hinge 12, the upper portion of the body section being reduced as shown at 13 so as to telescope into the cover section when closed, as shown in Fig. 2, to give a neat and attractive appearance. In one of these sections, preferably the body section, is mounted a loose powder container, preferably in the form of a flexible sack 14 of thin flexible sheet rubber, or, if preferred, the back wall may be made of any suitable material with the front wall 15 only of thin flexible sheet rubber. This front wall is provided with one or more slits 16 cut substantially at the center thereof without removing material. I have found it to be a property of this thin flexible rubber

sheet that when a slit is cut as indicated without removing any of the rubber material, under ordinary conditions the edges of the slit lie in contact with each other and in the same plane, so that the slit is normally closed and will not allow passage of the powder from the sack under ordinary handling, even though the powder is very fine, but if a puff is pressed lightly against the surface of this rubber sheet and passed back and forth in contact therewith the passage of the puff will cause the rubber sheet at one side of the slit to move inwardly away from the other side thus opening the slit to allow passage of the powder to the puff. The same effect may be secured by tapping this rubber wall of the sack with the puff, but as soon as the tapping or sliding movement of the puff ceases the sides of the slit come together again automatically, thus automatically closing the slit against passage of powder. Thus this flexible rubber wall forms an automatic closure to prevent passage of the powder from the container during ordinary handling, but will allow passage of the required amount of powder to the puff as required in the manner indicated, and no manipulation of the container itself is required to close the slit. Although I have shown but one slit in this flexible rubber wall, it will, of course, be understood that a plurality of slits may be provided if found desirable.

A convenient means of carrying this container is shown in Figs. 1 and 2 in which the container is held in the body section 10 by a spring clip 17 engaging the side walls of the body member and clamping the outer edges of the sack against the bottom of the container. This spring has a raised portion 18 at one side thereof to allow insertion of a finger nail so that the spring may be easily removed to allow removal of the powder container for filling purposes. After the old container has been removed a new container filled with powder may be inserted in its place, or the old container may be refilled through a suitable opening. In the form shown an opening 19 (Fig. 5) is left in one side of the sack or container which is normally held closed by a clip 20 substantially U-shaped in cross section and hinged at 21 to metal plates 22 secured to the walls of the sack on opposite sides of the opening 19. When closed this clip embraces these plates and the edges of the sack closing the filling

opening, but it may be swung to the dotted line position (Fig. 3) to allow separation of the plates for the purpose of feeding powder to the container. A mirror 23 may be mounted in the cover section 11, and any desired form of puff 24 carried in the box for use with this container.

In Figs. 6, 7 and 8, I have shown this flexible rubber container as enclosed in the puff itself. In these figures 25 represents the rear wall of a flexible sack which may be sheet rubber or any other suitable material, and 26 is the front wall of thin flexible sheet rubber provided with a slit 27 cut therein in the same manner as in the first form without removing material from the sheet. This sack when filled with powder is enclosed in the puff comprising the rear wall 28 of suitable cloth and the front wall 29 also of cloth having the usual wool surface 30 for applying the powder. This front wall is provided with a slit or opening 31 for passage of powder to the surface of the puff after it passes from the container to the slit 27. This container has a filling opening at one side edge thereof the same as shown in Figs. 3, 4 and 5 with the same type of closure 20, and a cloth loop 32 forms a handle for convenient use of this puff. As shown in Fig. 8 this puff is normally carried in a box comprising hinged cover and body sections 33 and 34, the same as in Figs. 1 and 2, with the usual mirror 35 in the cover section. This container in the puff holds the loose powder 36 without spilling under ordinary handling, the slit 27 being normally closed the same as in the first form. When it is desired to use the powder all that is necessary is to bend the puff backwardly along 40 a line at or adjacent the slit which will cause the sides of the slit to separate to allow passage of powder therethrough. The same effect may be secured by rubbing the puff on the surface to be powdered or patting the surface lightly with this puff.

It will be apparent from the foregoing description that I have provided a neat and attractive container for the loose powder which may be manufactured at low cost and in which the loose powder is always enclosed so that it cannot be contaminated with dirt, but is always easily accessible. The thin

flexible rubber wall acts as an automatic closure for the container so that no manipulation of covers or removing of closures is necessary in securing access to the powder. The powder is thus easily accessible at all times and the operator after use cannot forget to close the container. Therefore, there is no danger of spilling powder in the box. 60 As stated above this automatic closing effect for the slit in the rubber wall is secured by the action of the rubber tending, because of its resiliency, to return to a given plane, and thus to hold the side edges of the slit 65 together when there is no outside pressure tending to separate them.

Having thus set forth the nature of my invention, what I claim is:

1. A powder puff comprising a flexible 70 container having one wall of flexible sheet rubber provided with a slit made without removing material so that the slit is normally closed and closes automatically by the elasticity of the rubber, and a wool like covering for said wall constructed to allow passage of powder from said slit to the surface of the puff.

2. A powder puff comprising a flexible container having a wall of flexible sheet rubber provided with a slit cut therein which is normally closed and closes automatically by the elasticity of the rubber, and a cloth covering for said container having a woolly surface provided with an opening in alignment with said slit. 80

3. In combination, a box having cover and body sections, and a powder container in said box having a wall of flexible sheet rubber provided with a slit cut therein without removing material so that the slit is normally closed to retain the powder in the container and closes automatically by the elasticity of the rubber. 90

4. In combination, a box comprising cover 95 and body sections, and a puff in said box forming a powder container comprising a flexible sack having a wall of flexible sheet rubber provided with a slit cut therein which closes automatically by the elasticity of the 100 rubber, a cloth covering for said wall, and a handle for said puff.

In testimony whereof I affix my signature.

FRANZ VINCENT.
